H. J. STUART.
BUTTON CLASP.
APPLICATION FILED MAR. 29, 1916.

Patented Apr. 29, 1919.

Inventor
Henry J. Stuart
By his Attorney
Walter A. Faldee.

UNITED STATES PATENT OFFICE.

HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

BUTTON-CLASP.

1,302,449.

Specification of Letters Patent. Patented Apr. 29, 1919.

Application filed March 29, 1916. Serial No. 87,647.

To all whom it may concern:

Be it known that I, HENRY J. STUART, a citizen of the United States, residing at Derby, in the county of New Haven and 5 State of Connecticut, have invented a certain new and useful Improvement in Button-Clasps, of which the following is a specification.

My invention relates to button clasps, but 10 more particularly to those which are provided with a bar or support for carrying the looped extremity of the button tab, and its object is to so construct a clasp of this character that the button tab may be mounted 15 on its supporting bar after its looped extremity has been formed.

I attain this and other objects of my invention in the device set forth in the following description and accompanying drawings 20 in which like reference characters refer to corresponding parts.

In the drawings:

Figure 1 is a front view of my improved clasp, a part of the supporting webbing and 25 button tab being broken away;

Fig. 2, a central vertical section taken on line $x-x$ in Fig. 1, and

Fig. 3, a perspective view of the button tab.

Referring to Figs. 1 and 2, the clasp, which is shown loosely mounted on the looped extremity of the supporting strap A, consists of an attaching loop B and a button loop C and a button tab D which latter carries a button E. The attaching loop B is bent up out of a single piece of wire having its extremities terminating in its lower side forming the inwardly projecting pintles 2, 2 which latter have their adjacent extremities slightly separated for a purpose which will hereinafter appear. The button loop C, which is made of sheet metal, is provided with a tongue or strap 3 projecting from its upper side 4 which tongue is curled 40 to form a sleeve or bearing for the pintles 2, 2. Just below the upper side 4 the loop is provided with a bridge 5. All of the parts of the button loop C, with the exception of the tongue which forms the bearing 45 3, have their face portions struck up or beaded to give the necessary body and strength to the loop and at the same time to enable the loop to present the skeleton-like and ornamental appearance of a heavy

metal or wire device. The device thus far 55 described is one well-known in the trade and is disclosed herein merely for the purpose of showing how my invention is applied. The tab D has its extremities d, d attached to the under side of the base plate e of the 60 button E by a suitable adhesive substance thereby forming a loop which is carried by the bearing 3 and depends downwardly along the rear side of the button loop C in back of the bridge 5. When the button loop 65 C is blanked the upper side 4 together with the tongue which forms the bearing 3 is slit midway and vertically to form the slot 6 which is restricted at its upper extremity but widened as it approaches its lower extremity. 70 After the extremities d, d of the tab D have been fastened to the button base e so that the tab forms a loop one of the folds of this loop is passed upwardly from the rear through the opening 6 and thereby becomes 75 suspended from and supported by the bearing 3. In this manner the tab is attached to the clasp after a supporting loop has been formed therein. The opening left between the adjacent extremities of the pintles 2, 2 80 registers with the slot 6 thereby leaving an unobstructed passage for the looped extremity of the tab. Since the upper extremity of the slot 6 is restricted, that is to a width about equal to the thickness of the 85 tab, it prevents the fabric from passing back into the slot after the device has been assembled, and further the flaring entrance at the lower end of the slot 6 being between 90 rounded corners of the bead which forms the upper side 4 of the loop enables the tab to be readily inserted in the slot during the process of assembling. Heretofore it has been necessary to thread the tab around the upper side or other member of the button 95 loop to which it has been attached before fastening the extremities of the fabric, which would be impracticable in the present instance wherein the extremities are fastened to a button base in the manner above described, since this operation must be performed before the tab is attached to the clasp. It is understood, however, that the supporting loop in the tab may be formed in any other well known manner since the 100 broad feature of my invention resides in a construction wherein the closed supporting loop in the tab can be passed through an

105

opening in the supporting member of the clasp during the process of assembling the device.

While the device herein disclosed embodies the preferred forms of my invention, yet it is to be understood that the same is susceptible to such modification as may fairly come within the scope of the appended claims.

Having now described my invention what I claim and desire to protect by Letters Patent is:

1. A button clasp comprising a strap attaching loop, a button loop and a pivotal connection between said loops, the said pivotal connection being provided with an opening for the passage of a fold of a button tab into said attaching loop.

2. A button clasp comprising an attaching loop and a button loop, a sleeve carried by one of said loops and a cross bar carried by the other loop and journaled in said sleeve to form a hinge, the said hinge being provided with a transverse opening for the passage of a fold of a button tab into said loop.

3. In a button clasp having a button tab, an attaching loop with inwardly projecting pintles and a button loop provided with a sleeve in which said pintles are journaled to form a hinge, the said hinge being slit transversely for the passage of a fold of the button tab into the attaching loop.

In testimony whereof I have hereunto set my hand this 1st day of February, 1916.

HENRY J. STUART.
